UNITED STATES PATENT OFFICE

2,514,078

VIBRATING MACHINE

Clyde Lee, Mountain View, Okla.

Application July 19, 1946; Serial No. 684,941

1 Claim. (Cl. 259—75)

1

This invention relates to a mechanical vibrating device especially intended and adapted to subject molds for plastic materials, such as cement, to a vibratory action to accomplish a proper settling of the mixture while the mold is being filled to thereby eliminate the otherwise necessary step of tamping or compacting the mixture and to produce an article possessing more uniform characteristics.

More particularly, it is an aim of the invention to provide a machine having a vibratory platform on which the mixture receiving mold is detachably supported and which is preferably vibrated by a teeter-totter or rocking movement for agitating the mixture within the mold to uniformly compact the mixture.

Still another object of the invention is to provide a mechanism for the above described purpose of extremely simple construction which is capable of being economically manufactured and sold, which is durable and efficient in operation, and which is relatively light and capable of being readily moved about as required.

Numerous other objects and advantages of the invention will hereinafter become more fully apparent from the following description of the drawings, which illustrate a preferred embodiment thereof, and wherein—

Figure 1 is a longitudinal, substantially central sectional view of the vibrator machine;

Figure 2 is a top plan view thereof;

Figure 3 is a horizontal sectional view of the mold, taken substantially along a plane as indicated by the line 3—3 of Figure 1;

Figure 4 is a plan view of the vibratory mold supporting platform;

Figure 5 is a cross sectional view of the platform actuator;

Figure 6 is a transverse sectional view through the machine taken substantially along a plane as indicated by the line 6—6 of Figure 1, and

Figure 7 is a fragmentary longitudinal sectional view taken substantially along a plane as indicated by the line 7—7 of Figure 6.

Referring more specifically to the drawings, the vibratory machine in its entirety is designated generally 8 and includes a base 9 having a substantially flat upper surface and which is supported in an elevated position by depending corner legs 10, which are preferably at least eight

2

to ten inches in length and which may be of any desired length in excess thereof for supporting the base 9 at any desired level.

A suitable motor 11 is bolted or otherwise secured transversely of the base 9 and adjacent one corner thereof and is provided with a rotatably driven shaft 12 to an end of which is keyed a belt pulley 13. The motor 11 may be of any suitable structure, such as an electric motor, which is capable of rotatably driving the shaft 12.

The base 9 is provided with a pair of laterally spaced and laterally aligned upstanding bearings 14, disposed adjacent the end thereof on which the motor 11 is mounted. Each of the bearings 14 include a bearing block 15, an inverted U-shaped bolt 16 having legs extending downwardly through the block 15 and through the base 9 and provided with nuts 17 on the lower ends thereof. The bearings 14 also include a bushing 18 which is clamped by the bolt 16 and nuts 17 between the upper surface of the block 15 and the intermediate portion of the bolt 16. A shaft 19 is journaled in and extends through the bushing 18 and is provided with a belt pulley 20 on one end thereof and in longitudinal alignment with the belt pulley 13. An endless belt 21 is trained over the pulleys 13 and 20 for revolving the shaft 19 off of the shaft 12. The shaft 19 is provided with a longitudinally disposed eccentric or cam 22, which is disposed between the bearings 14 and which is welded or otherwise secured thereto, as seen at 23. The outer half of the cam or eccentric 22 is substantially semi-circular in cross section, as

clearly illustrated in Figures 1 and 5, for a purpose which will hereinafter become apparent. A rod or pipe 24, of circular cross section, is disposed on the upper side of and transversely to the base 9, substantially intermediate of the shaft 19 and the end of the base 9 which is remote thereto. The rod or pipe 24 is secured in position on the base 9 by means of a pair of spaced inverted U-shaped bolts 25 which are engaged thereover and which extend through the base 9 and are provided with threaded ends to receive nuts 26 for detachably clamping the member 24 in position on the base 9.

The pipe or rod 24 provides a fulcrum for the intermediate portion of a platform 27 which rests thereon and which is retained against lat-

eral displacement by the intermediate portions of the U-bolts 25 and which is held against longitudinal displacement by depending cleats 28, between which the intermediate portions of the rod or pipe 24 is disposed. The upper side of the platform 27 is provided with transversely disposed longitudinally spaced cleats 29, corresponding ends of which are connected by a longitudinally disposed cleat 30, which is disposed adjacent one longitudinal edge of the platform 27. A turn button or bar 31 is rotatably mounted intermediate of its ends on a shank portion of a headed pin 32 which is anchored in a side edge of the platform 27. The turn button or bar 31 is disposed on the side of the platform 27 remote to the cleat 30 and when in an upright position projects above the upper surface of said platform to cooperate with the cleats 29 and 30 for engaging the base of a mold 33 to retain the latter, detachably in position on the platform 27. The turn button 31 may be swung to a position parallel to the platform 27, in which position, it will be disposed below the upper surface of the platform to facilitate the removal of the form 33. A reinforcing strip 34, preferably of metal is countersunk in the upper surface of the inner end of the platform 27 and is provided with a depending flange 35 which engages against the inner end of the platform 27. The reinforcing strip 34 is secured in position by a plurality of driven fastenings 36.

The platform 27 is provided with a perpendicular bore 37, adjacent its outer, opposite end through which a portion of the shank of an elongated bolt 38 extends and in which said portion is loosely disposed. The bolt 38 is provided with a lower threaded portion which extends through the base 9 and which carries a nut 39 located therebeneath. An expansion coil spring 40 is disposed on the upper portion of the bolt shank, between its headed upper end and the upper side of the platform 27 and abuts against a pair of washers 41 which are located between the spring and the bolt head and platform.

The form 33 includes a bottom 42, an end wall 43, side walls 44 and 45 and an opposite end wall 46. The end wall 43 abuts against and rises from one end of the bottom 42 and the side walls 44 and 45 are swingably connected to the end wall 43 by hinges 47. The ends of the side walls 44 and 45 are provided with outwardly opening notches 48 to receive portions of the shank of a nut and bolt fastening 49 which is detachably engaged therewith for holding said last mentioned ends of the side walls in abutting engagement with the side edges of the end wall 46. The lower portion of the end wall 46 abuts against the opposite end of the bottom 42 and the outer side of said end wall abuts against cleats 50 on the side walls 44 and 45 and said end wall 46 is provided with a pair of upright cleats 51 on the outer side thereof and located between the cleats 50. The side wall 45 is provided with a pair of longitudinally spaced openings 52 to receive tubular matrices 53 which extend therethrough and which are provided with inner ends which extend slightly through and beyond openings 54 of the side wall 44, as best seen in Figure 3. The opposite ends of the matrices 53 project from the outer side of the wall 45 and are provided with bales 55 to facilitate the removal thereof.

From the foregoing it will be readily apparent that the form 33 may be filled with a cement mixture in a fluent form through the open top 56

thereof while the form 33 is supported on the platform 27. As the form 33 is thus being filled, it is vibrated by a rocking motion of the platform 27 relatively to the base 9 on the rod or pipe 24 as a fulcrum. This oscillation of the platform 27 is accomplished by the operation of the motor 11 for driving its shaft 12 and the shaft 19 through the belt and pulley connection 21, 13 and 20, all of which parts rotate in a counter-clockwise direction, as seen in Figure 1. As the shaft 19 is thus revolved in a counter-clockwise direction, its eccentric or cam 22 at each revolution thereof contacts the bearing strip 34 on the upper surface of the platform 27 for swinging the inner end of the platform 27 downwardly, to permit the cam or eccentric 22 to pass thereover. As the inner end of the platform 27 is thus swung downwardly, the outer end thereof is swung upwardly to compress the spring 40 which reacts to swing said outer end downwardly and back to its position of Figure 1 or therebeyond, when the bearing strip 34 is disengaged from the eccentric 22. This repeated teeter-totter type operation of the platform 27 and the mold 33 as the latter is being filled with the fluent cement mixture, not shown, insures proper settling of the mixture thus eliminating the necessity of tamping or otherwise compacting the mixture. After the mold 33 has been filled while being subjected to vibration, the mold may be removed by turning the button or bar 31 to a released position. The side and end walls are then removed by release of the fastening 49, after first removing the cores 53 and the block is left to set on the bottom 42 as a pallet to form a block having external dimensions corresponding to the internal dimensions of the mold 33 and having bores extending therethrough of diameters corresponding to the external diameters of the matrices 53. The side and end walls, cores 53, and fastening 49 are immediately reassembled for reuse with another bottom 42.

Platform 27 has been illustrated and described to oscillate in a teeter-totter manner on a fulcrum located substantially intermediate of its ends, but it will be readily apparent that the fulcrum 24 could be located adjacent either end of the platform and that the spring 40, for returning the platform to its canted position of Figure 1, could if desired, be located between the fulcrum and the eccentric or cam 22. Likewise, if desired, the platform 27 could be arranged to rock on a longitudinal rather than a transverse axis, as illustrated. Further, if desired, the oscillating platform 27 could be suspended from above to oscillate in the same manner and for the same purpose. Also, the platform 27 could be constructed to support and oscillate a plurality of molds simultaneously.

60 Numerous other modifications and changes are contemplated and may obviously be resorted to, without departing from the spirit and scope of the invention as hereinafter defined by the appended claim.

65 I claim:

An apparatus for compacting a fluent mixture in a mold, comprising a supporting base, a platform on which a mold for containing a fluent material is adapted to be mounted, said platform being fulcrumed intermediate of its ends on the base, a rotary driven element journaled above the base for striking the upper side of one end of the platform at each revolution thereof for rocking the platform in one direction, and spring means bearing on the upper side of the opposite end of

the platform for rocking the platform in the opposite direction when the striking element moves out of engagement therewith and for causing the last mentioned end of the platform to be swung forcibly against the base or the first mentioned end thereof to be swung against the driven element for rocking and vibrating the mold, and means for detachably positioning the mold on the platform and with the intermediate portion thereof disposed over the fulcrum.

CLYDE LEE.
